CLAIM

(57) The ornamental design for a garden stool, as shown and described.

DESCRIPTION

FIG. 1 is a top perspective view of a garden stool, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view in a folded configuration;

FIG. 10 is a top perspective view of the frame, with the seat cushion removed, shown separately to reveal aspects of the design that may not be apparent in other views;

FIG. 11 is an enlarged detail view of area 11 in FIG. 1; and,

FIG. 12 is an enlarged detail view of area 12 in FIG. 1. The dash-dot-dash broken lines in FIG. 1 show the boundaries encircling the enlarged views of FIGS. 11 and 12 and form no part of the claim.
